UNITED STATES PATENT OFFICE.

EDIA RAY RAMSEY, OF PENN YAN, NEW YORK.

GAME APPARATUS.

1,127,279.

Specification of Letters Patent.

Patented Feb. 2, 1915.

Application filed July 25, 1914. Serial No. 852,976.

To all whom it may concern:

Be it known that I, EDIA RAY RAMSEY, a citizen of the United States of America, and residing at Penn Yan, in the county of 5 Yates and State of New York, have invented new and useful Improvements in Game Apparatus, of which the following is a specification.

The principal object of my invention is 10 the provision of means whereby the various plays of a game, and particularly a baseball game, may be enacted before a player and which while not necessitating any particular skill or experience and therefore capable 15 of being played by all, is nevertheless governed by the skill and so-called "luck" of the player, just as in the regular game.

Another object is to simulate as far as 20 possible the actual conditions existing in the regular game.

The invention accordingly embodies a series of indicating devices arranged as operated to represent the various plays of a game, mechanism for controlling the operation 25 of the several indicating devices and an impact-receiving member connected to operate the controlling mechanism. The impact-receiving member, is usually, in the case of a baseball game apparatus, such as illustrated in the present disclosure, in the form 30 of a captive ball which is connected by a suitable flexible connection with a member which operates the control mechanism in accordance with the force and effect of the 35 blow upon the ball.

The indicating devices are preferably in the form of annunciators suitably connected with the control mechanism and serving as they are operated to visualize the various 40 plays made by a player.

A special feature consists in so arranging certain of the indicating devices that they will be successively operated and will indicate successive plays in the game and arranging other indicating devices to represent various plays modifying or bearing upon the successive plays made. Thus in 45 the present baseball game disclosure there is a first series of indicators governed by the force of the blow struck to show the 50 number of successive bases covered or "run" and a second series of indicators showing for instance the portion of the field into which the ball has been struck and whether 55 the player is "safe" or "out."

Various other objects and features of the

invention will appear as the specification proceeds.

The accompanying drawings illustrate in concrete form a practical embodiment of my 60 invention but it will be understood that the invention is susceptible of various changes and modifications without departure from the true spirit and scope thereof.

Figure 1, is a perspective view showing 65 the invention embodied in a baseball game apparatus. In this view the captive ball has just been struck by a player. Fig. 2, is a more or less diagrammatic view illustrating electrical connections between the 70 control mechanism and indicating devices, and showing the parts in the positions indicated in Fig. 1. Fig. 3, is a detail view of a form of annunciator employed with the indicator board appearing in section. Fig. 4, 75 is a front view of these parts looking at the face of the board. Fig. 5, is a face view 80 illustrating the operation of the "base" annunciators. Figs. 6 and 7 are detail plan and side views of one of the "base" contacts. 85 Figs. 8 and 9 are detail plan and side views of one of the play-modifying contacts. Fig. 10, is a detail plan view illustrating one of the switches for operating the "out" annunciators. Fig. 11 is a sectional view illustrating means for releasing the operating 90 disk of the control mechanism. Fig. 12, is a rear perspective view of a modified form of control mechanism. Fig. 13, is a sectional view of the same taken substantially on the 95 central plane of Fig. 12.

In the general view, Fig. 1, the impact-receiving member is shown as a captive ball 11, suspended by a rope or like flexible connection 12, in position to be struck by a 95 bat or club 13 in the hands of a player. To make the play more realistic the action of pitching the ball is simulated by supporting the ball in an elevated position and then allowing it to swing down toward the batter. Thus in the illustration the ball is releasably supported in elevated position by a pivoted catch 14 which when tripped by a pull on the line 15 allows the ball to swing around a guide 16 as a fulcrum point. The 100 "curving" of the ball may be imitated by making this fulcrum a variable one, as by supporting it on a flexible connection 17 which may at will be raised or lowered to change the trajectory of the ball.

The indicating devices are preferably mounted on a board 20 representing a ball

field and which is usually placed so that the player can observe the effect of his batting. Thus in the illustration the indicator board is placed at the inner end of a gallery and the player stands confronting the board so that he can see the effect of his own play and so that the whole effect can be observed by spectators at the other end of the gallery.

The control mechanism, designated 21 10 may be placed wherever convenient and it is here shown located at the outer end of the gallery at a point conveniently accessible to the operator or attendant who may be in charge of the gallery.

15 In the present disclosure the "first", "second", "third" and "home" bases are represented on the field by stations 29, 30, 31, and 32 respectively and the positions of "short stop", "left field", "center field" 20 and "right field" are represented by the stations 33, 34, 35 and 36. At each of these stations an annunciator is placed to indicate a play made at that particular station. Thus as shown diagrammatically in Fig. 25 2, there is an annunciator 38 for "first base", another one 39 for "second base", a third 40 for "third base" and a fourth 41 for "home", and annunciators 42, 43, 44 and 45 are provided at the stations of 30 "short stop", "left field", "center field" and "right field". In addition, certain "cut" indicating annunciators 46, 47, 48 and 49 are placed adjacent the respective bases to indicate the players "out" at such 35 stations and it will be understood that other annunciators may be provided to indicate various other plays at the respective bases. These annunciators, as more clearly indicated in Figs. 3 and 4 may be of the so-called "drop" type, wherein an electromagnet 51 serves when energized to attract its armature 52 and thereby to lift a trip hook 53 carried by said armature out of sustaining engagement with a pivoted drop 45 54. The drop when thus released falls down into the dotted line position shown. The magnets and wiring connections are preferably placed on the back of the board and the drops on the face of the board. Cords 50 55 or other means may be provided for resetting the drops, these cords being shown attached to the drops and passed upward through openings 56 to the back of the board. The base and field position annunciators are preferably so placed that their drops, when released, will cover the stations to which they relate and the drops will usually be provided with suitable inscriptions or figures to plainly indicate the 55 nature of the play. Thus as shown in Fig. 5, the drop for the first base annunciator bears the figure of a base runner on its under or normally concealed face so that when released the effect is given of a man 60 just reaching first base. The outer or nor-

mally exposed faces of the drops are preferably of the same color as the field so as to be normally indistinguishable. To prevent waste of current the annunciators may be caused when operating to break their own circuits by making the drops a part of the circuit as indicated at 57 in Fig. 3.

The control mechanism illustrated consists of a movable operating member and a plurality of control elements actuated thereby. The operating member is shown in the form of a disk 58 rotatably mounted on a supporting shaft 59 and provided with two projecting contact elements 60 and 61 to make electrical engagement with the control elements which are in the form of contacts disposed about the periphery of the disk on the base 62. The flexible connection which holds the ball captive is shown connected directly to the operating disk at 63 and the periphery of the disk is grooved to keep the flexible connection properly positioned thereon. The disk is held in a normal position of rest against a back-stop 64 by a spiral spring 65 or equivalent means, 90 this spring being shown connected at its inner end to the fixed supporting shaft and at its outer end to a stud 66 carried by the disk.

95 The control contacts are in the illustration arranged in two series, a first series of successively disposed contacts for indicating successive base-running movements and a second series of contacts arranged more or less arbitrarily to inject certain elements 100 of "chance" into the game. The first series consists of a contact 67, connected with the first base annunciator, a contact 68 for second base, a contact 69 for third base and a home base contact 70. These contacts are 105 disposed in the path of and are arranged to be engaged by the outstanding contact 60 of the operating disk. This moving contact 60 is charged with current by being connected with a slip ring 71 to which current is led by a connection 72 from a battery 73 or other current source. The rest of the circuit connections for the successive indicating devices are as follows: from the first base contact 67 by a conductor 75 to the 110 first base annunciator 38 and from there by way of a conductor 76 to the common return 77 which leads to the return side of the battery; from second base contact 68 by conductor 78 to second base annunciator 39 and from there by conductor 79 to the common return 77; from third base contact 69 by conductor 80 to third base relay 40 and from there by conductor 81 to common return 77; from home base contact 70 by 115 conductor 82 to the home relay 41 and thence to the common return 77 by a short conductor 83. These base contacts are usually made yieldable in both directions as by being pivoted on studs 84 yieldingly 120

held in a central position by springs 85 as indicated in Fig. 6.

The second or more or less arbitrarily arranged series of controlling elements are 5 illustrated as contacts for indicating the various field plays and for indicating the players "out." Thus the first one of these contacts shown, 87, serves when contacted by the projecting contact 61 on the drum to 10 cause actuation of the short stop annunciator and the "out" annunciator at first base, which would indicate the player out at first base on a ball to short stop. The connections by which this is accomplished are as 15 follows: The projecting drum contact 61 receives current from the slip ring 89 which is fed from the battery 90 or other current source by conductor 91, while contact 87 is connected by conductor 92 with the short 20 stop annunciator 42 and with the "out at first" annunciator 46 by a branch conductor 93, the annunciators being respectively connected by conductors 94 and 95 with a common return 96 to the other side of battery 25 90. These two annunciators thus operate in parallel. The player in Fig. 1 is indicated as making the play just described.

In advance of contact 87 there is shown a contact 98 for indicating a man safe at first 30 on a drive to right. This contact is accordingly connected by a conductor 99 with the right field annunciator 45, said annunciator being in turn connected by a conductor 100 to the common return 96.

35 The base contacts are operated successively in the forward rotation of the disk and the contacts of the second series are operated at the termination of the forward movement imparted to the disk. Accordingly 40 the backs and tips of this second set of contacts are faced with insulation, as indicated at 102 Figs 8 and 9 so that the engagement of the contact member 61 therewith on the forward movement of the drum 45 has no circuit-changing effect. The circuit is thus only closed through these contacts when contact member 61 moves forward past a contact and then upon the rearward rotation of the drum drops

50 back into engagement with the face of the contact. To permit the forward yielding action of the contacts they may be pivoted on studs 103. In order that the disk will be held in its most forwardly rotated position, back stops 104 may be provided for these forwardly yielding contacts, the springs 55 serving to normally hold the contacts back against these stops. These contacts thus serve as ratchets holding the drum in its advanced position and preventing the drum 60 swinging back and operating other contacts in rear of the foremost contact reached.

Suitable means may be provided for releasing the drum and thus in effect "resetting" the control mechanism. Means for

this purpose is illustrated in the form of a sleeve 107 on the shaft 59 arranged to be forced by a lever 108 into engagement with the angular retracting levers 109.

In the illustration the contact members 70 60 and 61 are slidably mounted in guides 110 and are pressed outwardly by springs 111. The angular retracting levers 109 are connected with the inner ends of these 75 slideable members and these retracting levers are operated by the sleeve 107.

The two play-modifying contacts 87 and 98 for first base, are preferably so arranged that the contact member 60 will have to travel far enough forward to operate the 80 first base contact before either one of them will be operated. Thus in the illustration a relatively light blow on the captive ball may serve to rotate the drum far enough to engage contact member 60 with first base 85 contact 67 but not far enough to carry contact member 61 farther than just in front of contact 87, whereupon annunciators 38, 42 and 46 will be operated to indicate the player out at first on ball to short stop, 90 while a slightly heavier blow may suffice to carry the drum far enough farther forward to engage contact member 61 in front of contact 98 whereupon the annunciators 38 and 45 will show the player "safe" at first 95 on a ball to right field. To insure the contact members 60 and 61 engaging only the sets of contacts with which they are intended to coact, said members, and the two sets of contacts are preferably disposed in different planes, as indicated in Fig. 9 and they may be of different lengths as also shown. The base running indicators may, if desired, be made to act only on "safe" plays.

In the present embodiment various play-modifying contacts are provided adjacent each base contact. Thus for second base there is an "out" to center field contact 114, and a "safe" to left field contact 115; for third base there is an "out" to right field 110 contact 116 and a "safe" to center field contact 117; and for home base there is an "out" to left field contact 118 and a "safe" to center field contact 119.

Contact 114 is connected by conductor 120 115 to center field annunciator 44, which in turn is connected to the common return 96 by conductor 121. Conductor 122 connects contact 115 with left field annunciator 43 and that annunciator is connected by conductor 123 with common return 96. Conductor 124—99 connects contact 116 with the right field annunciator 45, conductor 125—120 connects contact 117 to center field annunciator 44, conductor 126—122 connects contact 118 to left field annunciator 43 and a conductor 127—120 connects contact 119 to center field annunciator 44, all these annunciators being joined to the common return 96, as shown.

To avoid the possibility of conflicting plays, the "out" annunciations are usually controlled by independent switches, such as indicated at 130, 131 and 132 in position to be operated by the contacts 114, 116 and 118. These switches, as indicated in Fig. 10 may simply be in the form of spring arms 133 arranged to be pushed into contact with terminal plates 134 to complete circuits 10 through the "out" annunciations. One member of switch 130 is connected by a short back connection 135 with contact 114 so as to receive current when that contact is contacted by contact member 61 and 15 the other member of the switch is connected by conductor 136 with the "out" annunciator 47 at second base, said annunciator being connected by conductors 137-121 with common return 96. Switches 131 and 20 132 are similarly back-connected to take current from their respective operating contacts 116 and 118 and they are connected by conductors 138 and 139 respectively to the "out" annunciations 48 and 49 at third and 25 home bases, which annunciations are tapped to the common return as shown. The "out" annunciations are in this way switched in parallel with the field annunciations in conjunction with which they are intended to 30 operate.

In the modification illustrated in Figs. 12 and 13 the effect of men progressively running the bases is obtained by providing contact-controlling disks representing the men 35 and operating these disks in succession by successive blows on the impact-receiving member. For this purpose the operating disk 58 is provided with a pawl 141 arranged to first engage and operate the first disk 143, 40 then the second disk 144 and then the third disk 145. The three or more disks, representing as they do successive players are rotatably engaged on the supporting shaft 59 and are provided with springs 146 or 45 equivalent means tending to turn them back to a neutral position of rest.

Suitable contacts, such as before described, are provided to be operated by the respective disks. At the start the pawl 141 on the 50 driving disk 58 is in engagement with a shoulder 148 on the disk 143 representing the first man, so that the first blow on the impact-receiving member rotates the first disk forward a distance depending upon the 55 force and effect of the blow. The first disk may be held in the position to which it has been thus advanced by the forwardly yielding contact elements as previously described. As the spring 65 returns the drive 60 disk to its position of rest, the drive pawl 141 drops from engagement with the shoulder 148 on the first disk into engagement with a shoulder 149 on the second disk 144 so that upon the next blow, movement is 65 imparted directly to the second disk. The

second disk is provided with a pawl 150 on its face engaging with a ratchet ring 151 on the back of the first disk so that the second disk carries along with it the first disk. Upon the next retractive movement of the 70 drive disk 58, the drive pawl 141 drops into engagement with a shoulder 152 on the third disk so that upon the third stroke, the third disk is carried forward an extent dependent upon the force of the blow. A pawl 153 on the face of the third disk, engaging the teeth of a ratchet ring 154 on the back of the second disk, causes the second disk to move forward with the third disk and the first disk is at the same time advanced a corresponding extent by reason of the pawl and ratchet connection between the second and first disks. This successive operation of the disks gives the effect of one man assisting another as in the regular game and means 80 such as the "resetting" mechanism described above may be provided for returning the player in case of a player going "out," etc., and to meet the disks for the next play.

From the foregoing it is apparent the invention closely approximates the conditions existing in an actual game and therefore provides the interest and excitement usually afforded by the real game. Further 95 the invention provides an amusement device which can be played by any one and one which while decidedly effective and practical is both simple and inexpensive in construction.

What I claim is:—

1. Game apparatus comprising a series of indicating devices operable to represent the different plays of a game, mechanism controlling the selective operation of the 105 said indicating devices and a captive ball operatively connected with said control mechanism and supported in position to be struck by a club in the hands of a player.

2. Game apparatus comprising a series of 110 annunciation devices arranged when operated to represent the different plays of a game, control mechanism for the respective annunciation devices and a captive ball connected to operate said control mechanism 115 and supported in position to be struck by a club in the hands of a player.

3. Game apparatus comprising a series of indicating devices arranged as operated in 120 succession to represent successive plays in a game, a second series of indicating devices arranged to represent plays modifying the plays represented by the first series of indicating devices, control mechanism embodying a movable operating member, a series of 125 successively disposed control elements actuated by said operating member and operatively connected with the successive indicating devices and a series of arbitrarily disposed control elements actuated by the 130

operating member and operatively connected with the play-modifying indicating devices, and means for imparting movement to the movable operating member.

5 4. Game apparatus comprising a series of indicating devices arranged as operated in succession to represent successive plays in a game, a second series of indicating devices arranged to represent plays modifying the plays represented by the first series of indicating devices, control mechanism embodying a movable operating member, a series of successively disposed control elements actuated by said operating member 10 and operatively connected with the successive indicating devices and a series of arbitrarily disposed control elements actuated by the operating member and operatively connected with the play-modifying indicating devices, and a captive ball connected to the movable operating member for actuating the same.

5. Game apparatus comprising a series of indicating devices arranged to represent the successive base-running plays of a baseball game, a series of indicating devices arranged to represent plays modifying the base-running plays, an impact-receiving member and control mechanism embodying a movable operating member operatively connected with the impact-receiving member, a series of successively disposed control elements actuated by said operating member and operatively connected with the successive base-running indicating devices and a series of control elements actuated by the operating member and operatively connected with the play-modifying indicating devices.

6. Game apparatus comprising a series of indicating devices arranged to represent the successive base-running plays of a baseball game, a series of indicating devices arranged to represent plays modifying the base-running plays, an impact-receiving member and control mechanism embodying a movable operating member operatively connected with the impact-receiving member, a series of control elements operatively connected with the successive base-running indicating devices and arranged to be successively actuated by the operating member in the movement imparted to said member by the impact-receiving member, and control elements for the play-modifying indicating devices arranged to be actuated by the operating member at the end of the movement imparted thereto by the impact-receiving member.

7. Game apparatus comprising a series of indicating devices arranged to represent the successive base-running plays of a baseball game, a series of indicating devices arranged to represent plays modifying the base-running plays, an impact-receiving member and control mechanism embodying a movable

operating member operatively connected with the impact-receiving member, a series of control elements operatively connected with the successive base-running indicating devices and arranged to be successively actuated by the operating member in the forward movement imparted to said member by a blow on the impact-receiving member, means for returning the operating member to a normal position of rest and control elements for the play-modifying indicating devices arranged to be actuated by the operating member upon its return movement at the end of the forward movement imparted thereto.

8. In game apparatus, indicating devices arranged to represent the bases of a baseball field, indicating devices disposed adjacent the base indicating devices and arranged to represent plays made at the respective bases, an impact-receiving member and control mechanism for the indicating devices comprising an operating member operatively connected with the impact-receiving member, control elements for the base indicating devices arranged to be successively actuated by said operating member and control devices for the second-mentioned indicating devices arranged to be actuated by the operating member.

9. In game apparatus, indicating devices arranged to represent the bases of a baseball field, indicating devices disposed adjacent the base indicating devices and arranged to represent plays made at the respective bases, field-play indicating devices, an impact-receiving member and control mechanism for the indicating devices comprising an operating member operatively connected with the impact-receiving member, control elements for the base indicating devices arranged to be successively actuated by said operating member, control devices for the second-mentioned indicating devices arranged to be actuated by the operating member and control devices for the field-play indicating devices arranged to be actuated by the operating member.

10. In game apparatus, indicating devices arranged to represent a ball field, an impact-receiving member, and control mechanism for the indicating devices comprising a plurality of movable members operable in sequential order by successive blows on the impact-receiving member and control elements actuated by the said sequentially operable movable members.

11. In game apparatus, indicating devices arranged to represent a ball field, an impact-receiving member, and control mechanism for the indicating devices comprising a movable operating member operatively connected with the impact-receiving member, control elements connected to the indicating devices, a plurality of movable mem-

bers for actuating the control elements and means for sequentially coupling the operating member to successive ones of the movable control members.

5 12. In game apparatus, indicating devices arranged to represent a ball field, control mechanism for said indicating devices, a flexible connection from said control mechanism, a captive ball on said flexible connection, releasable means for supporting the ball in elevated position, a fulcrum for supporting the flexible connection as the ball is released and means for shifting said fulcrum to thereby vary the trajectory of the 15 ball.

13. Game apparatus comprising a series of indicating devices arranged to represent the successive base-running plays of a baseball game, an impact-receiving member, 20 control mechanism embodying a movable operating member operatively connected with the impact-receiving member, a series of control elements operatively connected with the successive base-running indicating

devices and arranged to be successively actuated by the operating member in the movement imparted to said member by the impact-receiving member, and means for releasing the operating member from the control elements. 25

14. In game apparatus annunciators arranged to represent the bases of a baseball field, annunciators disposed adjacent the base annunciators and arranged to represent plays made at the respective bases, an impact-receiving member and control mechanism for the annunciators comprising an operating member operatively connected with the impact-receiving member, control elements for the base annunciators arranged 30 to be successively actuated by said operating member and control devices for the second-mentioned annunciators arranged to be actuated by the operating member.
